UNITED STATES PATENT OFFICE.

ALEXANDER C. WILDY, OF NEW ATHENS, ILLINOIS.

METALLIC RAILWAY-TIE.

1,160,229.

Specification of Letters Patent. Patented Nov. 16, 1915.

Application filed April 13, 1915. Serial No. 21,068.

To all whom it may concern:

Be it known that I, ALEXANDER C. WILDY, a citizen of the United States, residing at New Athens, in the county of St. Clair and State of Illinois, have invented certain new and useful Improvements in Metallic Railway-Ties, of which the following is a specification.

My invention relates to railways, and more particularly to an improved railway tie therefor.

The primary object of my invention is to provide a railway tie which is simple in construction, cheap to manufacture, and one which is strong and durable and easily placed in position.

Another object of my invention is to provide a railway tie preferably formed of metal and having improved means thereon for fastening the rails in position.

A further object of my invention is to provide improved means associated with the tie for assisting in retaining the same in position, said tie being preferably hollow and having sound deadening means therein.

A still further object of my invention is to provide a railway tie preferably hollow throughout its length and having improved end caps therefor, said end caps being formed to receive the ballast of the roadbed so as to assist in preventing dislodgment of the tie.

With the above and other objects in view my invention resides preferably in the construction, combination, and arrangement of parts as hereinafter set forth in the specification and illustrated in the accompanying drawings, in which—

Figure 1 is a fragmentary top plan view of a railway tie embodying the improvements of my invention, only two of the retaining plates for the rail being shown in retaining position. Fig. 2 is a fragmentary longitudinal sectional view of the same.

Fig. 3 is an end elevation of my improved railway tie showing the same in position on a roadbed. Fig. 4 is a transverse sectional view taken on the line 4—4 of Fig. 1 and looking in the direction of the arrows.

Fig. 5 is a detail perspective view of one of the retaining plates. Fig. 6 is a detail perspective view of one of the end caps. Fig. 7 is a side elevation of one of the fastening bolts. Fig. 8 is an end elevation of the same.

Similar reference characters indicate simi-

lar parts throughout the various views of the drawings.

Referring more particularly to the drawings in which the preferred embodiment of my invention is illustrated, I provide a railway tie having a body formed of substantially rectangular configuration, said body being preferably of cast metal and having a top wall 1, bottom wall 2, and side walls 3 and 4. The top and bottom walls 1 and 2 extend beyond the side walls 3 and 4 as shown to advantage in Figs. 3 and 4 to provide longitudinally extending top flanges 5 and 6, said top wall being likewise extended as at 7 to provide a laterally extending end flange for a purpose which will hereinafter be set forth. The bottom wall 2 is extended similarly to the top wall 1 to provide side and end flanges, these flanges being respectively designated 8, 9 and 10. Upon reference to Fig. 4 it will be noted that the points at which the flanges 8 and 9 join the end walls 3 and 4, respectively, are squared; that is, a recess is provided between the top and bottom flanges 5 and 8, 6 and 9, respectively, 80 said recesses being squared at their bases so as to more readily receive and retain the ballast in a manner which will be hereinafter set forth.

As shown to advantage in Figs. 2 and 4 85 the tie is preferably formed hollow, a suitable fibrous material designated 11 being receivable within the tie so as to deaden the metallic sound which would be produced by the operation of railway trains over the 90 same. In order to strengthen the tie, I provide a vertically disposed longitudinally extending web 12, said web 12 being disposed between the top and bottom walls 1 and 2 of the tie and serving to divide the same into 95 two chambers in which the sound deadening material hereinbefore referred to is deposited and packed. Said web 12 terminates short of the length of the tie as shown to advantage in Fig. 2 and the end cap 13 having 100 a lateral flange 14 forming a closure substantially U-shaped in cross section is receivable within the open end of the tie, said cap being forced thereinto until the inner 105 face of the wall 13 abuts the end of the web 12 as shown at 15. This serves to retain the sound deadening material in position, the ballast used on the roadbed serving to retain the end cap in position in a manner which 110 will become apparent hereinafter.

It is to be understood that in actual practice any suitable fastening means, such as rivets, bolts, or the like may be provided for positively securing the end caps 13 in 5 position.

I provide rail retaining clamps, these clamps comprising plates 16, said plates 16 being angularly offset as at 17 to provide jaws 18 for engagement with the base 19 of a rail 20 of the usual form. Said plates 16 are securable on the tie by means of clamping bolts 21, suitable apertures 22 being provided in the top flanges 5 and 6 of the tie, through which said bolts 21 are adapted 15 to pass. The plates 16 are provided with elongated apertures 23 adapted for registration with the apertures 22 in the flanges 5 and 6, the bolts 21 being provided with enlargements 21' adjacent the upper end 5 20 thereof which are complementary in size to the openings 23 whereby to prevent lateral movement of the plates and undue lost motion.

In building a railway employing my improved railway tie a plurality of the latter may be disposed in the usual manner, and the ballast deposited therebetween. The peculiar formation of the end and bottom flanges 8, 9 and 10 will serve not only to prevent sinking of the tie in soft earth but will 25 serve to receive the ballast for "tamping," the ballast also being receivable in the end caps of each tie whereby to prevent lateral, as well as longitudinal movement of the tie 30 relative to the direction of travel and also to retain the end caps in position. The rails may now be secured in position and the clamping plates 16, of which there are preferably 4 to each rail on each tie, may be 35 bolted into their relative positions in engagement with the base of a rail and tightened to prevent lateral and longitudinal movement of the rail. It will be understood that I may employ rivets or similar fastening 40 means for the plates 16, but the present showing is preferable.

From the above description taken in connection with the accompanying drawings, it is thought that a clear and comprehensive 50 understanding of the construction, use, and advantages of my improved railway tie

should be readily gathered and it will be noted that I have provided a tie which not only serves to secure a railway rail thereon, but also co-acts with the ballast of the 55 roadbed to tend toward stability of construction and also for providing sound deadening means, which not only may deaden sound, but also strengthens the tie.

While I have shown and described my invention as possessing a peculiar form and construction, it is desired that it be understood that I may make such changes in the details thereof that do not depart from the spirit and scope of the invention as claimed. 60 65

Having thus described my invention, what I claim and desire to secure by Letters Patent is:

1. A railway tie, including a hollow rectangular body having an anchoring flange 70 on its base, the top wall of said body being extended to provide longitudinally extending flanges, means thereon for securing of a rail thereto, a strengthening web within said rectangular body, and end caps therefor abutting against said web, as and for the purpose set forth.

2. A railway tie, including a hollow rectangular body, means associated therewith to anchor said tie, strengthening means 80 within the hollow rectangular body, rail securing means associated therewith, closures for said body, said anchoring means and closures being adapted to receive ballast to facilitate retention of the tie in position. 85

3. A railway tie, including a hollow rectangular body having a longitudinally extending strengthening partition terminating short of the ends of said body, ballast receiving and rail-supporting flanges formed 90 on the bottom and top marginal edges of said body, and hollow end caps receivable in said body abutting the ends of said partition adapted to receive ballast, whereby to retain said caps in position. 95

In testimony whereof I affix my signature in presence of two witnesses.

ALEXANDER C. WILDY.
